UNITED STATES PATENT OFFICE.

GEORGE I. PAIGE, OF DENBIGH, NORTH DAKOTA.

STORM-WINDOW.

1,287,409.

Specification of Letters Patent. Patented Dec. 10, 1918.

Application filed March 8, 1918. Serial No. 220,782.

To all whom it may concern:

Be it known that I, GEORGE I. PAIGE, a citizen of the United States, residing at Denbigh, in the county of McHenry and State 5 of North Dakota, have invented certain new and useful Improvements in Storm-Windows; and I do hereby declare the following to be a full, clear, and exact description of the invention, such as will enable 10 others skilled in the art to which it appertains to make and use the same.

This invention relates to storm windows and more particularly to an adjustable frame structure for supporting the window sash 15 of a storm window structure, or for supporting screen so that the glass sashes or panels may be removed in summer time and replaced with screens or vice versa, as necessary or desired and the primary object of 20 the invention is to provide a frame structure which is adjustable to fit various sized windows.

A further object of this invention is to provide an adjustable frame structure which 25 includes adjustably connected sections each of which is composed of a pair of plates having horizontal flanges for engagement with a window frame and parallel perpendicular portions extending inwardly from the 30 flanges, upon the inner ends of which parallel portions are formed sash gripping portions for gripping the sashes which carry the panes or screens of the storm window structure and further to provide suitable 35 ventilating openings in certain of the sections the sizes of which may be regulated by sliding panels.

With the foregoing and other objects in view this invention consists in such novel 40 features of construction, combination and arrangement of parts as will be hereinafter more fully described, illustrated in the accompanying drawings and claimed.

In describing the invention in detail, reference will be had to the accompanying 45 drawings wherein like characters designate like and corresponding parts throughout the several views and in which:

Figure 1 is a side elevation of the improved storm window structure.

Fig. 2 is a section on the line 2—2 of Fig. 1.

Fig. 3 is a perspective view of one plate of one of the sections which forms the base 55 of the frame structure.

Fig. 4 is a horizontal section on the line 3—3 of Fig. 1.

Fig. 5 is a section on the line 4—4 of Fig. 1.

Fig. 6 is a horizontal section on the line 5—5 of Fig. 1 showing a section through the mid-rail of the sash.

Fig. 7 is a vertical section on the line 6—6 of Fig. 1 showing a vertical section through the mid-rail of the sash.

Fig. 8 is a section on the line 7—7 of Fig. 1 showing one of the vent openings and the closure plate therefor.

Fig. 9 is a detail perspective of one of the plates of which the section of the mid-rail of the sash is composed, and

Fig. 10 is a detail perspective of the glass holder or receiving member of the mid-rail structure.

Fig. 11 is a detail section through the base portion of the sash on the line 8—8 showing the ventilating openings of the ventilating plate closed.

Fig. 12 is a detail section through the base portion of the sash on the line 9—9 showing the same in use as a screen holding frame.

Referring more particularly to the drawing, 1 designates an ordinary window frame in which the improved storm window frame 85 structure 2 is positioned.

The base portion which is generically indicated by the numeral 3, is composed of a pair of adjustably connected sections 4 and 5.

The section 4 is composed of plates 6 and 7 while the section 5 is composed of plates 8 and 9. The inner ends of the plates 6 and 8 and the plates 7 and 9 overlap and they are provided with alining slots 10 through 95 which a thumb screw 11 extends. A wing nut 12 is mounted upon the screw 11 for holding the sections 4 and 5 in various adjusted positions.

The plates 6, 7, 8 and 9 have horizontally extending base flanges 14 formed upon their lower edges the under surface of which flanges rest upon a strip of felt or analogous packing material 15. The strip 15 of packing material is mounted upon the upper horizontal side 16 of a ventilating member 17 the front or outer side 18 of which is provided with ventilating openings 19. The base 20 of the ventilating plate 17 rests upon the window ledge indicated at 21 and 110

suitable guides 22 are carried by the inner surface of the side 18. The guides 22 support a plate 23 which may be slid over the ventilating openings 19 for preventing the passage of air through these openings and into the interior of the room, when desired.

The plates 6, 7, 8 and 9 have horizontally extending flanges 24 formed upon their upper ends and extending outwardly therefrom. Vertical portions 25 extend upwardly from the outer edges of the horizontal portions 24 and they are adapted to extend along the sides of the sash or frame 26 of the panel of the storm window. The upper ends of the sides 25 are bent inwardly as shown at 27 to extend over the substantially triangular putty which is placed in the window to hold the glass or pane 28 in the sash or frame 26.

The plates 6 and 8 are provided with ventilating openings 29 which have suitable guides 30 positioned on their upper edges. Closure plates 31 are slidably carried by the guides 30 for controlling or regulating the sides of the openings 29 or completely closing these openings. The inner plates 7 and 9 are provided with openings 32 which align with the openings 29 formed in the plates 6 and 8 so as to allow the air which passes through the openings 29 to pass into the room.

The top 34 of the frame structure 2 is composed of sections 35 and 36 each of which sections is composed of inner plates 37 and outer plate 38 the meeting ends of which overlap for adjustably connecting the sections 36 and 37. The sections 36 and 37 are held in adjusted position with respect to each other by a screw 39 and a wing nut 40 which screw extends through slots 41 formed in the overlapping ends of the sections. The plates 37 and 38 are provided with portions analogous to the portions 24, 25 and 27 of the plates 6, 7, 8, and 9 for engaging the upper sides of the upper sash 42 which carries the upper pane of glass 43.

The sides 44 and 45 of the frame 2 are identical in construction, each being composed of adjustably connected sections 46 and 47 which are connected through the medium of the screws 48 and wing nut 49, which screws extend through slot 50 formed in the overlapping ends of the plates of which the side pieces 44 and 45 are formed. The plates 51 and 52 of which each of the sections 46 and 47 of the sides 44 and 45 are formed have base flanges 53, parallel portions 54 and sash engaging portions 55. Positioned about all of the outer edges of the sashes 26 and 42 are felt or padding strips 56 which engage the inner surfaces of the horizontal portion of the various plates to make the storm window structure practically air tight.

The mid-rail structure which generically indicated by the numeral 60 is composed of a pair of telescopically connected sections 61 and 62 each of which is composed of a pair of plates 63. The plates 63 are provided with slots 64 through which a screw 65 extends so that by tightening the wing nut 66 upon the screw 65 the sections 61 and 62 may be held in adjusted position, in accordance with the adjustment of the top 34 and bottom 75 3 of the storm window frame.

Each of the plates 63 is provided with a socket structure 64 and its outer end which extends over the side engaging portion of the plate 64 of which the sections 46 and 47 80 of the sides 44 and 45 are formed. Perforated ears 66 extend outwardly from the outermost sides of the socket 64 and they receive bolts or pins 67 which attach the plate 63 to the side sections 44 and 45.

Positioned between the facing sides of the plates 63 are upper and lower pane receiving members 68 and 69. The members 68 and 69 are substantially U-shaped in cross section for receiving the lower edge of the upper pane 43 and the upper edge of the lower pane 28 for connecting these glass or transparent panes of the window structures to the mid-rail structure of the storm window panes.

While in the foregoing description, the invention has been described as an adjustable sash for storm windows, it is to be understood that this sash may be employed for holding screens, during the warm or summer 100 season.

In Fig. 12 of the drawings, a section through the base portion is shown, illustrating the sash used as a screen holding device. When the frame is used for holding screens, 101 the mid-rail structure 60 is detached from connection with the sash, and the various plates of the sash are loosened, to permit the removal of the transparent panes therefrom. The lower edge of the screen, which is indicated at 80 in Fig. 12 is folded upon itself and placed between the facing edges of the inclined portion 27 of the plates 6 and 7, being clamped therebetween. Bolts 81 are inserted through the openings 82 11 formed in the straight vertical portion 25 of the plates 6 and 7 and through the folded end of the screen for holding the same properly in place. The edges of the screen are then placed between the facing edges of the angled portions of the plates which form the vertical sides of the sash structure and the upper end of the screen is folded upon itself and inserted between the facing edges of the angled portions 37 and 38 of 12 the plates which form the top of the window frame. Suitable bolts similar to the bolts 81 are inserted through the openings 84 formed in the angled portions of the plates which form the top of the sash and also 13

through openings 85 formed in the angled portions of the plates which form the sides of the window sash, thereby securely holding the screen in proper position within the frame to form a screen thereof.

5 In reducing the invention to practice, certain minor features of construction, combination and arrangement of parts may necessitate alterations to which the patentee is entitled provided such alterations are comprehended within the scope of what is claimed.

What is claimed is:

1. An auxiliary window comprising an adjustable base portion, an adjustable top portion, adjustable side portions, means for holding said portions in adjusted position, and sash engaging portions formed upon the inner edges of said adjustable portions.

2. An auxiliary window comprising an adjustable base portion, an adjustable top portion, adjustable side portions, and means for holding said side portions in adjusted position, said adjustable portions each being composed of a pair of metallic plates 25 disposed in opposed parallel relation, the inner edges of said plates being bent to form sash engaging portions.

3. An auxiliary window comprising an adjustable base portion, an adjustable top portion, adjustable side portions, means for holding said side portions in adjusted position, said adjustable portions each being composed of a pair of metallic plates disposed in opposed parallel relation, the inner edges of said plates being bent to form sash engaging portions, and cushioning pads positioned within said side engaging portions.

4. An auxiliary window comprising an adjustable base portion, an adjustable top portion, adjustable side portions, means for holding said side portions in adjusted position, said adjustable portions each being composed of a pair of metallic plates dis-

posed in opposed parallel relation, the inner edges of said plates being bent to form sash 45 engaging portions, cushioning pads positioned within said side engaging portions, and a perforated ventilating frame attached to and depending from the under surface of said base portion.

5. An auxiliary window comprising an adjustable base portion, an adjustable top portion, adjustable side portions, means for holding said side portions in adjusted position, said adjustable portions each being 55 composed of a pair of metallic plates disposed in opposed parallel relation, the inner edges of said plates being bent to form sash engaging portions, cushioning pads positioned within said side engaging portions, 60 and a perforated ventilating frame attached to and depending from the under surface of said base portion, said base portion provided with a plurality of ventilating openings, and closure plates for said openings. 65

6. An auxiliary window comprising an adjustable base portion, an adjustable top portion, adjustable side portions, means for holding said portions in adjusted positions, each of said adjustable portions comprising 70 a pair of parallel plates, the inner edges of said plates bent to form sash engaging portions, a mid-rail, said mid-rail comprising upper and lower substantially U-shaped plates for receiving the lower edge of a side 75 panel, and a plurality of adjustably connected frames attached to said adjustable side portion and held in engagement with said U-shaped portion.

In testimony whereof I affix my signature 80 in presence of two witnesses.

GEORGE I. PAIGE.
